FILM DRYING METHOD AND APPARATUS

Hamilton P. Ellis, Fort Sheridan, Ill.

Application July 19, 1941, Serial No. 403,200

8 Claims. (Cl. 34—10)

This invention relates to improvements in film-drying machines and methods of drying films while wound on film reels or spools of the kind commonly used in developing tanks.

The principal object of the invention is to provide a novel form of machine and method for drying the film rapidly and safely while wound on such reel or spool, including means for automatically indicating to the operator when the film is completely dry and ready for removal.

In carrying out my invention I provide a cabinet having a cylindrical receptacle open at the top for receiving the film reel with the film wound thereon. Means for supplying heated air under pressure is connected to the lower end of the receptacle so as to force air upwardly through the air vents in the opposite ends of the film reel in order to pass between the adjacent surfaces of the film. The air current is capable of manual control so that when the film and reel are initially inserted in the receptacle in wet condition the amount of air is adjustable so that it is not quite sufficient to lift the reel and its film on account of the weight of the water adhering to the film surfaces. An auxiliary weighting device is also employed in connection with the reel corresponding substantially in weight to the amount of water that would normally adhere to a film of predetermined length. The arrangement is such that when the weighting means is mounted on the film reel and the air current initially adjusted so that the reel is not quite supported or in floating condition on the air current, the heated air will pass endwise through the film reel and film to dry the film surfaces. Due to the loss of weight of the water during this drying process, the reel will gradually rise or float on the current of air within the receptacle until the film is thoroughly dry, at which point an electric contact member is engaged to close a circuit indicating that the film is ready for removal.

The air current is preferably supplied by a blower having an intake disposed within the cabinet and protected by suitable filtering means so as to avoid the depositing of dirt, lint or the like on the film surfaces while drying. I also provide selective means for controlling and maintaining the air current at the proper drying temperature so as to avoid the danger of overheating or scorching the film in the hands of inexperienced operators.

The invention may best be understood by reference to the accompanying drawings, in which Fig. 1 is a perspective view of a cabinet type

film-drying apparatus constructed in accordance with my invention.

Fig. 2 is a detail plan view of a film reel of the type especially adapted for use with the apparatus shown in Fig. 1.

Fig. 3 is an enlarged vertical section taken transversely of the cabinet illustrated in Fig. 1, and showing the film reel in drying position therein.

Fig. 4 is a plan view of the cabinet, with parts broken away to show interior details, and with the film reel removed.

Fig. 5 is a vertical section taken longitudinally of the cabinet.

Fig. 6 is a wiring diagram showing the several electric control connections used with the apparatus.

Fig. 7 is a detail view of a plurality of stoppers of various weights which may be used with films of various sizes.

Referring now to details of the embodiment of the invention illustrated in the drawings, the apparatus is for convenience enclosed in a cabinet 10, and comprises as its main elements a cylindrical receptacle 11 mounted at the top of the cabinet and opening upwardly, and a blower or fan 12 mounted in the cabinet and discharging into the bottom of said receptacle through a duct 13.

The receptacle 11 is of proper size to receive a film reel 14 which herein is of the well-known type commonly used with a developing tank (not shown), and consisting of a hollow hub 15 having opposed parallel end discs 16, 16 with spiral grooves formed in their inside faces so as to receive the edges of a film 9 therein when the latter is wound on the reel in the usual manner, so as to hold the adjacent surfaces of the film in spaced relation. A series of slots or openings

17, 17 are formed as usual in the end discs, primarily designed to permit free access of the developing solution to the film surfaces during the developing operation. It will be understood that in the usual manipulation of such reels, the film is developed and rinsed while wound on the reel, but the film is usually unwound and hung endwise in air for drying. As will presently appear, I make use of the reel in a novel manner for drying the film without unwinding it from the reel.

The blower 12 includes rotor blades 20 propelled by an electric motor 21 as usual. An intake duct 22 leads to the blower from the exterior of the cabinet, through a suitable air filter 23, herein consisting of a mesh screen 26 across the

end of said intake duct, a perforated plate 24 spaced from said screen and forming part of the side wall of the cabinet, a casing 25 connecting the end of the said intake duct with the plate 24, and with suitable filtering material 27 such as wool in said casing.

An electric heating element 28 of any suitable form, herein consisting of coiled resistance wires, is disposed in the air discharge duct 13 leading to the receptacle 11.

Means for controlling the volume of air supplied to the receptacle is also provided, herein consisting of a vane or plate 30 mounted on a horizontal shaft 31 having suitable bearings 31^a, 31^b in the cabinet, and extending through the front wall of the cabinet, with a knob 32 and pointer 33 fixed on its outer end. The vane is mounted to swing into and out of a slot 34 in the air intake duct 22 so that the volume of air supplied to the blower and finally entering the receptacle 11 can be controlled by manipulation of the knob 32 on the front of the cabinet.

The operation of the apparatus may now be described as follows:

After the film is developed and rinsed on its reel 14 in the usual manner, the reel and film are transferred directly to the receptacle, as indicated in Figs. 3 and 5, with the bottom flange of the reel resting by its own weight on the bottom of the receptacle.

In connection with the apparatus, I provide one or more weighted members, herein in the form of stoppers or corks 36, 36^a. In practice, one of these stoppers is inserted in the open upper end of the hollow hub 15 of the reel. A plurality of stoppers of different weights are preferably provided as a part of the apparatus for selective use, depending upon the size or length of film to be dried in each instance.

With the proper stopper inserted in the reel, the blower is turned on so that the air current is forced upwardly through the slots 17, 17 in the reel and between the adjacent film surfaces. This air current, of course, has a tendency to lift the entire reel, but by means of the control knob 32 the volume of air is initially adjusted at the start of the drying operation so that the combined weight of the reel which includes the film 22 and the stopper 36, is approximately counterbalanced by the air blast, and rests on the bottom of the receptacle just short of floating on the air current. It will be understood, of course, that the water on the film assists in weighting down the reel. As drying proceeds, the loss of water from the film permits the reel to rise gradually and float on the air current in the receptacle until said reel reaches a predetermined level at which the film is entirely dry.

At this predetermined level, a suitable stop, herein consisting of an electric switch member 38, is mounted adjacent the rim of the receptacle (see Figs. 4 and 5). In the preferred form shown, said contact member comprises two contact springs 39, 40 suitable insulated from each other on an upright shaft 41 mounted on the top wall of the cabinet adjacent the rim of the receptacle. The free ends of the contact springs 39, 40 can thus be swung laterally by means of a turning knob 42 on shaft 41, into and out of registering position over the said receptacle, to facilitate insertion or removal of the reel.

The stop signal arrangement just described is such that when the film is thoroughly dried, the reel 14 is lifted or floated to the predetermined level to engage switch 38 and close it automati-

cally, causing actuation of a signal device, such as a bell 43.

It will now be understood that the stopper member 36 serves the double purpose of adding sufficient weight to the film reel (as determined by initial experiment) to insure the proper floating action of the reel for a given size or length of film to be carried thereby, and also to close the central hollow opening usually formed through the hub 15 of commercial forms of film reels so that most of the drying air will be forced through the main body of film reel. It will be understood further, however, that the film reel itself may be especially designed and weighted so that a stopper 36 may be dispensed with.

The electrical connections employed with the apparatus above described is illustrated in the wiring diagram, Fig. 6. The main supply conductors 45, 46 are connected to a source of power as usual. The signal bell 43 with its contact switch member 38 are connected across said conductors. Likewise, the blower motor 21, with its control switch 21^a are connected across said main conductors. For convenience the switch 21^a is mounted on the front wall of the cabinet, as shown in Fig. 1.

As a preferred arrangement for controlling the air heating element 28, I provide a switch 28^a and a fixed resistance 47 arranged to be connected in series therewith through a double-throw switch 48 so that in one position of the latter switch the heating element will deliver air to the receptacle only at a moderate temperature sufficient to dry the film without danger of damaging the latter due to overheating. A signal light 49 may be connected in parallel with the fixed resistance so as to indicate when the moderate, film-drying current is turned on. In the other position of switch 48, the fixed resistance 47 is cut out, so that the air temperature will be somewhat higher if desired for other purposes. With the arrangement illustrated, however, the operator will know that the apparatus should not be used for drying film unless the signal lamp 49 is lighted.

It will be understood, of course, that various modifications in the control circuits may readily be employed. For instance, instead of the signal light 49, a signal light can be used in parallel with the heating circuit when the fixed resistance 47 is cut out, to serve as a warning to the operator that the air blast is too hot for film drying. These, and other modifications in air blast and electric control devices may be employed without departing from the spirit and scope of my invention as defined in the appended claims.

I claim as my invention:

1. The method of drying film on a vented film holder of the type used in developing tanks, which consists in placing the film holder with a film mounted thereon into a receptacle, forcing a blast of drying air upwardly through said receptacle, with the volume of said blast and the combined weight of the reel initially adjusted so that the holder and film may be approximately counterbalanced by said air blast while in wet condition, but will be freely floated on said air blast to a predetermined higher level when the film is dry.

2. In a film-drying apparatus, a vented holder adapted to hold a film, a receptacle for said holder, air blast means connected with the bottom of said receptacle in a direction tending to float said holder on a column of air produced by said air blast means, and control means for adjusting the volume of air from said air blast

means so that the combined weight of said film holder may be approximately counterbalanced by said air blast when the film on said holder is wet, and be floated by said air blast means to a predetermined higher level in said receptacle when the film has become dried.

3. In a film-drying apparatus, a vented film holder, a receptacle for said holder, air blast means connected with the bottom of said receptacle in a direction tending to float said holder on a column of air produced by said air blast means, and control means for initially adjusting the volume of air from said air blast means so that the combined weight of said film holder may be approximately counterbalanced by said air blast when the film on said holder is wet, and be floated to a predetermined higher level in said receptacle when the film has become dried by said air blast, and signal means including a control member arranged to be actuated by said film holder for automatically effecting operation of said signal means at said predetermined level.

4. In a film-drying apparatus, a vented holder, a receptacle for said holder, air blast means connected with the bottom of said receptacle in a direction tending to float said holder on a column of air produced by said air blast means, auxiliary weighting means detachably connectible to said film holder, and control means for adjusting the volume of air from said air blast means so that the combined weight of said film holder may be substantially counterbalanced by said air blast when the film on said holder is wet, and be floated to a predetermined higher level in said receptacle when the film has become dried by said air blast.

5. In a film-drying apparatus and in combination with a vented film reel having a hollow spool, a receptacle for said film reel, air blast means connected with the bottom of said receptacle, auxiliary weighting means for said reel adapted to be inserted in the open end of said hollow spool, control means for adjusting the volume of air from said air blast means so that the combined weight of said reel may be substantially counterbalanced by said air blast when the film on said reel is wet and be floated to a predetermined higher level in said receptacle when the film has become dried by said air blast means.

6. In a film drying apparatus, a vented film

holder, a cabinet, a receptacle for said holder mounted on the top of said cabinet, air blast means within said cabinet connected with the bottom of said receptacle, an air inlet for said air blast means opening through the wall of said cabinet and having air filtering means therein, and control means for adjusting the volume of air from said air blast means so that the combined weight carried by said film holder may be approximately counterbalanced when the film on said holder is wet, and said reel may be floated to a predetermined higher level in said receptacle by said air blast when the film has become dried.

7. In a film-drying apparatus, a vented holder adapted to hold a film, a receptacle for said holder, air blast means connected with the bottom of said receptacle in a direction tending to float said holder on a column of air produced by said air blast means, and control means for adjusting the volume of air from said air blast means so that the combined weight of said film holder may be approximately counterbalanced by said air blast when the film on said holder is wet, and be floated by said air blast means to a predetermined higher level in said receptacle when the film has become dried, and an electric heating element for said air blast means including a fixed resistance in series therewith to guard against overheating of said air blast.

8. In a film-drying apparatus, a vented holder adapted to hold a film, a receptacle for said holder, air blast means connected with the bottom of said receptacle in a direction tending to float said holder on a column of air produced by said air blast means, and control means for adjusting the volume of air from said air blast means so that the combined weight of said film holder may be approximately counterbalanced by said air blast when the film on said holder is wet, and be floated by said air blast means to a predetermined higher level in said receptacle when the film has become dried, an electric heating element for said air blast means including a fixed resistance in series therewith to guard against overheating of said air blast, and visual signal means associated with said heating circuit to indicate when the apparatus is safe for film drying.

HAMILTON P. ELLIS.
